(57) **CLAIM**

The ornamental design for a shaving razor bottle, as shown and described.

DESCRIPTION

FIG. 1 is a front perspective view of a design of a shaving razor bottle showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is rear perspective view thereof.

The dash broken lines shown illustrate portions of the shaving razor bottle and form no part of the claimed design.

1 Claim, 5 Drawing Sheets
